United States Patent Office.

J. H. GODWIN, OF SCOTLAND NECK, NORTH CAROLINA.

Letters Patent No. 79,066, dated June 23, 1868.

IMPROVEMENT IN HAMMERS.

The Schedule referred to in these Letters Patent and making part of the same.

TO ALL WHOM IT MAY CONCERN:

Be it known that I, J. H. GODWIN, of Scotland Neck, in the county of Halifax, and State of North Carolina, have invented a new and useful Combined Hammer, Rule, Screw-Driver, Nail-Holder, and Tack-Claw; and I do hereby declare that the following is a full, clear, and exact description thereof, which will enable others skilled in the art to make and use the same, reference being had to the accompanying drawings, forming part of this specification.

The object of this invention is to combine, in a very simple and inexpensive way, a hammer with a series of implements used most generally in connection with it, so that several tools or implements may be manufactured in connection with a hammer nearly as cheap as the hammer alone.

In the accompanying sheet of drawings—

Figure 1 is a side view of my invention.

Figure 2, an end view of the same.

Figure 3, a detached view of the end of the handle of the same.

Similar letters of reference indicate like parts.

A represents the handle of a hammer, which may be constructed of wood as usual, and B the hammer-head, constructed of steel, or iron, and in any of the known forms. The handle A is graduated into inches, and eighths thereof, as shown in fig. 1, and in the end of the handle there is a screw-driver, C.

The hammer-head is provided with the usual nail-claw D, one of the prongs of which is provided with a V-shaped notch, a, to serve as a tack or brad-claw, (see fig. 2,) and in the inner side of the hammer-head there is made a V-shaped groove, b, extending longitudinally from the face of the hammer to the socket c which receives the end of the handle. The inner end of this groove is formed with a recess, d, to receive the head of a nail, the body of the latter being fitted in the groove b, and its end projecting beyond the face of the hammer, as shown in red in fig. 1. By this arrangement a nail may, preparatory to driving it, be stuck into a board or any wood-work beyond the reach of the operator, or when at such a distance as to preclude him from holding the nail with one hand and at the same time admit him striking it with the hammer in the other hand.

In using the screw-driver, the hammer-head serves as a lever. The device may be manufactured at a very small advance above that of the hammer alone, and will prove a very useful combination of implements for mechanics generally, especially for out-door work, where tools are carried in boxes, as portability is obtained and considerable time saved in handling, for where a plurality of tools is used, and the tools changed at short intervals, a great deal of time is expended in taking up and laying them down, and searching for them when mislaid or out of place.

Having thus described my invention, I claim as new, and desire to secure by Letters Patent—

As an improved article of manufacture, the tool, consisting of the combination of a hammer with graduated handle and tack-claw with a screw-driver, constructed as described.
